UNITED STATES PATENT OFFICE.

ELI F. WINEMAN, OF JOLIET, ILLINOIS.

TOWEL-RACK.

SPECIFICATION forming part of Letters Patent No. 323,478, dated August 4, 1885.

Application filed July 22, 1884. (No model.)

To all whom it may concern:

Be it known that I, ELI F. WINEMAN, a citizen of the United States of America, residing at Joliet, in the county of Will and State 5 of Illinois, have invented certain new and useful Improvements in Towel-Racks, of which the following is a specification, reference being had therein to the accompanying drawings.

10 Figure 1 is an end view, and Fig. 2 is a perspective view, having a towel applied.

This invention consists in certain improvements in towel-racks for holding either an endless towel or an ordinary straight towel; and 15 the improvement consists, principally, in the part for clamping and holding an ordinary straight towel.

Referring to the drawings, E represents the back board, by means of which the rack is 20 attached to the wall, to the face of which is attached, by proper screws, the lugs A, to which the spring-clamp B is pivoted at F. The spring S, inserted between the back board and one end of the clamp B, causes the opposite end to press firmly on the apex of the lug D', between which lug and the end D of clamp B an ordinary towel may be clamped and held, as shown in Fig. 2. The upper end of the towel is represented as folded over front, so 25 the fringe will hang over front and furnish a better place for the clamp to grasp the towel where it is doubled, so as not to injure the

towel, and for ornamentation. The lug D' is rounded on its apex, while the clamp is hollowed or concave, as shown at D, Fig. 1, for 35 the purpose of increasing the contact-surfaces and to render the parts less liable to injure the towel. The spring-clamps B are also provided with a series of integral arms, c c' c'', for 40 the purpose of supporting an ordinary roller, R, by means of its journals J, for the purpose of holding the endless towel T, as shown in Fig. 1. The arms c c' c'' also furnish means for supporting a towel by hooking loops that may be on it on these arms. Any kind of a 45 spring may be used other than the coil-spring shown to operate the clamp, if desired.

Having thus described my invention, what I claim as new, and desire to secure by Letters Patent, is as follows, to wit:

The towel-rack described, consisting of the back board, E, having the lugs A and D', (a pair at each end,) in combination with the spring-clamps B B, each pivoted centrally to a lug, A, on said back board, and each having a series of hooked arms, c c' c'', and a concave lug, D, roller R, and spring S S, located between the upper ends of said clamps and said back board, as and for the purpose set forth.

ELI F. WINEMAN.
